J. J. HIGGINS

VALVE FOR EXHAUSTING MACHINES

Filed July 21, 1922

FIG. 1

FIG. 3.

FIG. 2.

INVENTOR
JOHN J. HIGGINS

BY *J. J. Higgins*
ATTORNEY

UNITED STATES PATENT OFFICE.

JOHN JOSEPH HIGGINS, OF EAST ORANGE, NEW JERSEY, ASSIGNOR TO WESTINGHOUSE LAMP COMPANY, A CORPORATION OF PENNSYLVANIA.

VALVE FOR EXHAUSTING MACHINES.

Application filed July 21, 1922. Serial No. 576,492.

To all whom it may concern:

Be it known that I, JOHN JOSEPH HIGGINS, a citizen of the United States, and a resident of East Orange, in the county of Essex and State of New Jersey, have invented a new and useful Improvement in Valves for Exhausting Machines, of which the following is a specification.

This invention relates to apparatus for exhausting electric incandescent lamp bulbs and relates more particularly to an improvement in the manifold and valve mechanism of such apparatus.

An object of the invention is to provide means whereby the exhaust tube of a lamp bulb may be conveniently disposed in sealed communication with a vacuum line.

Another object of the invention is to provide means for conveniently and expeditiously ejecting an exhaust tube from association with an exhaust machine after a lamp has been tipped off.

Another object of the invention is to provide mechanism for effectively sealing a vacuum line from the atmosphere in such manner as to prevent the entrance of air to any appreciable portion of the line.

A still further object of the invention consists in providing coordinating machine elements which will operate to secure the exhaust tube of a vessel in sealed communication with a vacuum line and to effect the ejecting of said tube without affording atmospheric communication to said line or to the vessel.

Other objects will be apparent from the following description.

Machines for producing vacuum in lamp bulbs are well known in the art. Such machines usually comprise a pump having a valve consisting of a disc movable upon a nether plate and having suitably disposed ducts in given relative positions and connected with intermediate passages, which, in turn, afford communication to a plurality of communicating passages, the latter terminating in tube-supporting members. The

disc valve is operable to open and close the ports or ducts leading to the supports to successively evacuate the several lamps positioned in the supports. It is often necessary to provide for the preliminary evacuation of the bulbs, after which they are evacuated a second or even a third time to the proper degree.

The present invention, however, is directed to a combined valve and support in which the exhaust tube of a lamp may be inserted and provides means whereby an exhaust tube may be resiliently held in sealed communication with a vacuum line for evacuation after which the bulb may, as usual, be tipped-off, leaving the surplus or remaining portion of the tube in the support.

This tube, by means of the present invention, may be automatically ejected and, at the same time, the ejecting means serves as a closure for the passage in which the tube was previously positioned.

It will be readily appreciated that the means for simultaneously closing the aperture as the tube is ejected provides a more efficient machine than the one employing the expensive and heretofore-considered indispensable valve plates. On certain machines it is possible to eliminate the valve plates, and my valve may be connected directly to the vacuum-producing apparatus. Furthermore, where it is desirable to first exhaust a vessel and then fill the same with a gas, such, for instance, as one of the rare gases which may be comparatively expensive, it is an advantage to avoid the loss of any of such gas during the filling operation, and the present device makes this economic filling of envelopes possible.

The supports in which the exhaust tubes are inserted for the evacuation of bulbs are usually positioned as close to the valve of the vacuum pump or machine as is possible. However, for practical reasons, there is always a considerable length of passageway intermediate the supports and the pump. Heretofore, when a lamp had been exhausted

and the tipped-off tube had been removed from the support, the passageway or duct from the support to the valve of the exhaust machine had been left open to the atmosphere. Since the duct constitutes a part of the vacuum line, it is obvious that, during such exposure, this section of the line will accumulate an amount of moisture on the walls or other portions thereof, and it is well known that the entrance of moisture into the vacuum system will prove detrimental to efficient operation of the pump.

The present invention provides means for avoiding the exposure of any appreciable portion of the vacuum line to the atmosphere and thus the line may be maintained dry and the detrimental effects of moisture be eliminated.

One embodiment of the invention is illustrated in the accompanying drawing in which,—

Fig. 1 is a vertical section of my valve applied to a vacuum apparatus which is indicated in dotted lines;

Fig. 2 is a diagrammatic view of a plurality of valves connected to a vacuum-producing machine; and,

Fig. 3 is a diagrammatic view of a plurality of the valves as applied to another type of exhaust machine.

In the drawing, my valve is indicated, as a whole, by the numeral 4 and may comprise a casing 5 having discs 6 and 7 fitted tightly to the inner wall thereof and so disposed as to provide a chamber 8. The chamber 8 has connected thereto a tubular passage 9 which may be connected to a vacuum-producing apparatus 10, indicated in dotted lines, to afford communication between the chamber 8 and the apparatus. Within the casing 5 and disposed between the disc 6 and a screw plug 11 is a resilient member 12 having an axially disposed passage or aperture 13 therein.

When the member 12 is in position, the aperture 13 may be positioned in alignment with an aperture 14 in the plug 11 and an aperture 15 in the disc 6, thus providing communication between the chamber 8 and the exterior of the casing 5. The member 12 may be of any suitable material or construction to give the desired resiliency in the wall of the passage 13; soft rubber being preferable. This passage may be of less diameter than the exterior diameter of the exhaust tube of a bulb which is to be inserted therein, and the tube will thus be resiliently retained by the wall of the passage to provide a hermetic seal.

The opposite end of the casing 5 is provided with a plunger 16, reciprocable in a packing 17, which may consist of any suitable elastic material disposed between a threaded collar 18 and the disc 7. As an added assurance against leakage of air into

the chamber 8, liquid 19 is provided and so disposed as to surround the piston and be confined in the casing 5, between a screw collar 20 and the collar 18.

The plunger 16 is, therefore, movable within the casing 5 and may be thrust through the aperture 15 and into the passage or aperture 13 for the purpose of normally closing this passage and effectively sealing the chamber 8 from the atmosphere.

In order to provide a more firm contact between the walls of the passage 13 and the plunger, the plunger is provided with an enlarged portion 21 which, when thrust to position, as indicated in dotted lines, will make more firm contact with the walls of the passage 13. The passage being thus closed, a vacuum may be created in the chamber 8, and an exhaust tube 22 of a lamp bulb 23 may then be thrust into the passage 13, thus producing a hermetic connection between the chamber 8 and the bulb 23. The chamber 8 being connected with the vacuum line, the plunger 16 may be then withdrawn from the passage 13 and the lamp may be evacuated after which the plunger may be again inserted into the passage 13 to close the same, and the usual tipping-off fires may be applied to the constricted portion of the exhaust tube 22 and the lamp tipped-off, leaving the lower portion of the tube within the passage 13.

The plunger 16 may then be moved upwardly until it makes contact with the lower end of the tube 22, and a continued upward movement of the plunger will operate to eject the tube, after which the plunger may be moved downwardly within the passage 13 to such position as to permit the insertion of another exhaust tube, after which it may be withdrawn into the chamber 8 and another lamp may be evacuated. If desirable, the plunger 16 may be provided with a second enlargement in order to insure a sufficient contact area between the wall of the passage 13 and the plunger during the ejection of the exhaust tube.

When the head 21 of the plunger is in position to eject a tube from the passage 13, it will be noted that the passage is entirely cut off from the atmosphere, and, if desirable, the plunger may be so operated that, after moving upwardly to eject a tube, it will be left free for downward movement when engaged by another exhaust tube during the insertion of the same into the passage. On the other hand, the plunger may be adapted to be moved downwardly a sufficient distance within the passage for the free entrance of an exhaust tube. In this case, any air which may enter the passage can only do so for a distance equal to the length of the inserted portion of the exhaust tube, and moisture that may have accumulated on the inner wall of the passage

13 will be dissipated and confined between the exterior wall of the tube and the wall of the passage.

When my improved valve is employed in machines of the stationary exhaust type, considerable advantage is derived, inasmuch as such machines employ an elongated manifold which presents a considerable surface upon which condensate may form. A stationary exhaust machine is indicated diagrammatically in Fig. 3 and comprises a manifold 25 to which a plurality of my improved valves may be connected. The manifold may be in communication with an apparatus for producing three degrees of vacuum. A preliminary exhaust may be had through a duct 26 having a valve 27, and a second degree of vacuum may be produced through duct 30 having a valve 28, and a final degree of vacuum may be had through a duct 29 having a valve 31, the respective valves being operated to open or close the respective ducts to effect the successive exhausting operations. The machines for producing these different degrees of vacuum are well known and the present illustration is entirely diagrammatic to illustrate a general application of my invention.

It will readily be seen by the above description that my invention provides for the support of a lamp, simplifies the mechanism for the evacuation of the lamps and also provides for the ejection of a tipped-off tube from the support. A device of this character is of considerable importance in the art, inasmuch as its great simplicity reduces the initial cost and obviously reduces the cost of maintenance of exhaust machines.

This invention provides a support but, since it also includes a valve, it will be termed, in at least some of the claims, as a valve for the exhaust machines.

Although a preferred embodiment of the invention has been described and illustrated, it is obvious that other modifications may be made therein without departing from the spirit and scope of the appended claims.

What is claimed is:

1. A valve for exhaust machines comprising means for securing an exhaust tube in a vacuum line and means for automatically ejecting said tube and simultaneously closing said line.

2. A valve for exhaust machines comprising means for securing a tube in air-tight communication with a vacuum line and means for disconnecting said tube and simultaneously closing said line.

3. A valve for an exhaust machine comprising a resilient member having a passage for the reception of an exhaust tube and means movable within said member for ejecting said tube and for closing said passage.

4. A valve for an exhaust machine having means for securing a tube in air-tight com-

munication with a vacuum line, a reciprocable plunger for removing a tube from said line and means associated with said plunger for hermetically sealing said line.

5. A valve for an exhaust machine comprising a casing, a vacuum-producing apparatus, communication between said casing and said apparatus, a resilient member in said casing having an aperture for receiving and resiliently retaining an exhaust tube and means for opening or closing said passage and for ejecting said tube therefrom.

6. A valve comprising a casing, a plunger movable in said casing, a passage having resilient walls, a chamber in communication with said passage, a vacuum line, a conduit between said chamber and said line, and means associated with said plunger to engage with the walls of said passage and to eject a tube when disposed therein.

7. A valve comprising a casing, a plunger movable in said casing, a passage having resilient walls, a chamber in communication with said passage, a vacuum line, a conduit between said chamber and said line, said plunger being adapted to enter said passage and be resiliently engaged by the walls thereof to close said passage.

8. A valve comprising a casing, a plunger movable within said casing, a communicating passage within said casing having resilient walls for resiliently engaging a tube when forced into said passage, said plunger being movable to eject said tube and to effectively close said passage.

9. A valve comprising a casing, a plunger movable in said casing, a passage having resilient walls, a chamber in said casing and a passage connecting said chamber with the atmosphere, said plunger being operable to eject a tube from said passage and to simultaneously close said passage from the atmosphere.

10. A valve comprising a casing having an air-tight packing, a plunger movable in said packing, a resilient member having a relatively small passageway therethrough, a chamber in said casing disposed between said packing and said resilient member, a vacuum line and means to afford communication between said chamber and said line, said plunger being movable into and out from said passage to close or open the same and to eject an exhaust tube when positioned therein.

11. A valve for an exhaust machine comprising a casing having a passage adapted to constitute a portion of a vacuum line and to engage resiliently with an exhaust tube of a vessel and means for ejecting said tube and sealing said passage against the entrance of air to any appreciable portion thereof.

12. A valve for an exhaust machine comprising a casing, a resilient passage within

- said casing for receiving an exhaust tube of a vessel, a plunger movable within said passage, an enlarged portion on said plunger for engagement with said exhaust tube to eject the same from the passage and for sealing the passage from the atmosphere.
13. A valve for an exhaust machine comprising a casing, a plunger movable in said casing, a vacuum line, means for securing

the exhaust tube of a vessel in air-tight communication with said line, said plunger being operable to seal said vessel from said line and to eject said exhaust tube.

In testimony whereof, I have hereunto subscribed my name this 20th day of July 1922.

JOHN JOSEPH HIGGINS.
